UNITED STATES PATENT OFFICE.

RICHARD B. DALY, OF WOONSOCKET, RHODE ISLAND.

SLUBBER OR FLY-FRAME.

No. 895,541.

Specification of Letters Patent.

Patented Aug. 11, 1908.

Application filed September 21, 1907. Serial No. 393,902.

To all whom it may concern:

Be it known that J. RICHARD B. DALY, a citizen of the United States, and resident of Woonsocket, county of Providence, State of Rhode Island, have invented an Improvement in Slubbers or Fly-Frames, of which the following description, in connection with the accompanying drawing, is a specification, like letters on the drawing representing like parts.

This invention relates more particularly to slubbers or fly-frames, and it has for its object the production of novel and efficient mechanism for positively driving the bobbin-shafts from the "compound" on the main shaft in such manner that an absolutely uniform speed of the bobbin-shafts will be maintained at all times throughout the traverse of the bobbin-rail.

As will hereinafter appear the construction of the mechanism forming the subject matter of my invention is simple, there is no liability of its getting out of order, it can be readily applied, and is wholly automatic in its operation.

The various novel features of my invention will be fully described in the subjoined specification and particularly pointed out in the following claims.

Figure 1 is a vertical section of a sufficient portion of a slubber or fly-frame to be understood, with one practical embodiment of my invention applied thereto; Fig. 2 is a top plan view of the mechanism shown in Fig. 1.

The main shaft A, bobbin-rail B vertically reciprocated by usual mechanism (not shown) and positioned in such movement by the guide E; the bobbin-shafts C and D by means of which the bobbins, not shown, are rotated through usual intermediate gearing, and the meshing gears C^x, D^x, on the bobbin-shafts, may be and are all of well known construction and operate in a manner familiar to those skilled in the art.

Upon the main shaft is loosely mounted a hub 1 having a radial extension 2 longitudinally recessed to receive one end of a transmitter-carrier, shown as an arm 3 adjustably secured to the extension 2 by a clamping bolt 4 extended through a longitudinal slot 5, Fig. 1, in said extension.

Upon the outer or free end of the carrier 3 is formed a sleeve-like, lateral bearing 6, Fig. 2, in which is rotatably mounted the shaft 7 of the transmitter, which comprises said shaft and two sprockets 8, 9 as herein shown.

A driving member, shown as a sprocket 10, is mounted on the main shaft A and connected with the hub F of the usual compound gears, not shown, said member 10 being connected by a sprocket-chain or driving connection 11 with the sprocket 8 of the transmitter, whereby rotation of the latter is effected.

The driving connection 11 is maintained properly taut by longitudinal adjustment of the carrier 3, as will be obvious, the carrier having a vertical swinging movement upon the shaft A so that the transmitter will have a bodily movement concentric with the driving member or sprocket 10.

A driven member, shown as a sprocket 12, is fixedly secured to the bobbin-shaft D, and a sprocket-chain 13 connects said driven member and the sprocket 9 of the transmitter, whereby rotation of the latter effects rotation of the bobbin-shafts C and D.

It will be seen from the foregoing that the transmitter is connected by the separate connections 11 and 13 with the driving member 10 and driven member 12, respectively, so that a positive and very direct drive is effected between said driving and driven members.

Upon the end of the bobbin-rail B I have mounted means to support vertically the transmitter and to govern its movement transversely to the rail as the latter rises and falls, and herein such means consists of an upright plate 14 clamped in place by bolts 15, Fig. 1, extended through slots 16 in the plate, whereby adjustment of the latter is effected.

The upper edge of the plate 14 is shaped to present a cam 17 upon which the bearing 6 is slidably supported, the cam being a circular arc having the center of the bobbin-shaft D as its center. The connection or chain 13 is maintained properly taut by adjustment of the cam-plate or support 14, as will be apparent.

As the bobbin-rail rises and falls the support 14 will cause the transmitter to rise and fall in absolute unison therewith, the carrier 3 rocking on its fulcrum A, and at the same time the transmitter will have a back and forth movement upon and relatively to the cam 17.

As the cam is concentric with the bobbin-shaft D and the driven member or sprocket 12 it will be manifest that the back and forth movement of the transmitter will not in any way affect the slightest rotative movement

of the driven member 12, all rotative movement thereof being due solely to rotation of the sprocket 9 of the transmitter. So, too, the swinging movement of the carrier 3 from one to the other of its extreme positions will not cause any rotative movement whatever of the transmitter sprocket 8, or of the shaft 6, and as a consequence there is neither gain nor loss, at any time during the traverse of the bobbin-rail, in the rotative movement of the driven member 12 derived from the driving member 10 through the intervening connections. Accordingly the speed of the shafts C and D will be absolutely uniform at all times throughout the traverse, with no possibility of back lash or lost motion, and resulting in an even wind to the yarn. At the same time the power is transmitted from the driving member to the driven member 12 positively and directly, in an extremely simple manner, and with no tendency of the mechanism to get out of order.

The transmitter has a movement which is positively governed by the arm or carrier on which the transmitter is mounted and by the supporting cam, upon which the transmitter-bearing has a sliding movement.

In actual practice I am enabled, with the construction herein shown and described, to move the bobbin-rail from one to the other end of its stroke (the main shaft being at rest) without the slightest angular movement of the bobbin-shafts.

Having fully described my invention, what I claim as new and desire to secure by Letters Patent is:-

1. In a slubber or fly-frame, in combination, a driving sprocket, a vertically movable bobbin-shaft having an attached driven sprocket, a transmitter, connections between it and the said sprockets, to rotate the driven sprocket and bobbin-shaft from the driving sprocket, and means to cause the transmitter to move concentric with both sprockets throughout the vertical movement of the bobbin-shaft.

2. In a slubber or fly-frame, in combination, a driving member, a driven member, a vertically movable bobbin-shaft rotatable with said driven member, a transmitter, means to effect bodily movement thereof concentric with both members during vertical movement of the bobbin-shaft, and separate, positive driving connections between the transmitter and said driving and driven members.

3. In a slubber or fly-frame, in combination, a driving member, a driven member, a vertically movable bobbin-shaft rotatable with said driven member, a duplex connection between said members, a transmitter common to both parts of such connection, and means to cause said transmitter to move vertically in unison with the bobbin-shaft while maintaining constant distances from

the axes of rotation of the driving and driven members.

4. In a slubber or fly-frame, in combination, a driving sprocket, a vertically movable bobbin-shaft having an attached driven sprocket, a transmitter, a swinging carrier therefor fulcrumed co-axially with the driving sprocket, a sprocket-chain connecting the latter and the transmitter, a second chain between the latter and the driven sprocket, whereby the latter is rotated positively by the driving sprocket, and means to vertically support the free end of the carrier and cause the transmitter to move bodily concentric with the driven sprocket during vertical movement of the bobbin-shaft.

5. In a slubber or fly-frame, a driving sprocket, a longitudinally-adjustable carrier fulcrumed co-axially therewith, a transmitter rotatably mounted on said carrier and comprising two connected sprockets, a chain connecting one of them and the driving sprocket, a vertically movable bobbin-shaft, a driven sprocket fast thereon, a chain connecting said sprocket with the second one of the transmitter sprockets, and a vertically adjustable cam upon which the transmitter is slidably and vertically supported, said cam being concentric with the driven sprocket.

6. In a slubber or fly-frame, a driving sprocket, a carrier fulcrumed co-axially therewith, a transmitter rotatably mounted on the carrier and comprising two connected sprockets, a chain connecting one of them and the driving sprocket, means to maintain the chain taut, a vertically movable bobbin-shaft having an attached driven sprocket, a chain connecting it and the second sprocket of the transmitter, and means to effect vertical movement of the transmitter in unison with the bobbin-shaft and maintain the second chain taut, the transmitter moving bodily concentric with the bobbin-shaft.

7. In a slubber or fly-frame, a driving sprocket, a vertically swinging carrier fulcrumed co-axially therewith and having at its free end a lateral bearing, a shaft rotatably mounted in the bearing and having an attached sprocket at each end, a chain connecting one of said sprockets and the driving sprocket, a vertically movable bobbin-shaft, an attached driven sprocket, a chain connecting it and the second of the sprockets on the carrier, and a cam vertically movable in unison with the bobbin-shaft and upon which the bearing on the carrier rests and is slidably, substantially as and for the purpose described.

In testimony whereof, I have signed my name to this specification, in the presence of two subscribing witnesses.

RICHARD B. DALY.
